BUTTON CLAMP

Franklin A. Reece, Brookline, Mass., and Samuel W. Avis, Providence, R. I., assignors to The Reece Button Hole Machine Company, Boston, Mass., a corporation of Maine

Application April 30, 1936, Serial No. 77,178

18 Claims. (Cl. 112—114)

This invention relates to machines for sewing or otherwise attaching buttons to work, and particularly to the clamps for positioning and holding the buttons for the action of the attaching instrumentalities.

The invention has for its general object to provide an improved button holder or clamp of this character wherein, to a greater degree than in similar devices as heretofore proposed, a substantially flat perforated button will be accurately positioned and securely held, said device being readily adjustable both for the purpose of accommodating buttons of a wide variety of sizes and shapes and also to position the button at a variable distance from the face of the work, whereby to determine the length of the neck or shank by which the button is connected with the work.

The foregoing and other objects of the invention, together with means whereby the latter may be carried into effect, will best be understood from the following description of a preferred embodiment thereof shown in the accompanying drawings, this, however, having been chosen for purposes of exemplification merely, as it will be obvious to those skilled in the art that the invention, as defined by the claims hereunto appended, may be otherwise embodied without departure from its spirit and scope.

30 In said drawings:

Fig. 1 is a side elevation, partly broken away, of a portion of a button sewing machine equipped with a button clamp embodying the invention.

35 Fig. 1a is a horizontal section taken substantially on the line 1a—1a, Fig. 1.

Fig. 2 is a plan view, partly in section on the line 2—2, Figs. 1 and 4, and on a somewhat larger scale than Fig. 1.

40 Fig. 3 is a front elevation of the parts shown in Fig. 2.

Fig. 4 is a side elevation, partly broken away.

Fig. 5 is a longitudinal section taken substantially on the line 5—5, Fig. 2.

45 Fig. 6 is a fragmentary sectional view, taken substantially on the line 6—6, Fig. 2, showing the mounting of one of the clamping jaws.

Fig. 7 is a perspective view, partly in section, of the top plate and associated parts constituting a portion of the button clamp assembly.

Fig. 8 is a perspective view of the assembled clamping jaws and their carriers.

Fig. 9 is a perspective view of the bottom plate and associated parts.

55 While the invention is not limited in its ap-

plication to any particular type of button attaching machine, for convenience it is herein illustrated in connection with a button sewing machine of the character shown and described in an application filed January 24, 1936, by 5 Franklin A. Reece, Serial No. 60,616, wherein all of the lateral movements necessary to attach either a two-hole or a four-hole button are imparted to the stitch-forming instrumentalities as distinguished from the work-holding instrumentalities. Said machine comprises a base 15 supporting a work plate 16 and an overhanging head 17 in which is suitably guided a needle bar 18 carrying a needle 19 which cooperates with underthread or looper mechanism 20 to 10 attach to work W supported on the work plate 16 a flat perforated button B held by a combined presser foot and button clamp assembly C. The assembly C is normally pressed toward the work W to clamp the latter on the work plate 16 and 15 hold the button B in properly positioned relation thereto, but may be raised, before and after the attaching operations, to permit the insertion, removal or positioning of the work and the insertion and removal of successive buttons. 20 As shown, said assembly is provided with a short upright stem 21 connected by an arm 22 with a slide 23 guided for vertical movement in the head 17. The slide 23 is normally held downward to urge the combined clamp and presser 25 foot against the work by a spring 24 but may be moved upwardly against the tension of said spring to raise the assembly by a lever 25 connected by a chain 26 with a suitable treadle 27.

Referring to Figs. 2 to 9, the assembly C includes upper and lower plates 29 and 30 held in spaced parallel relation by studs 31, 32, 33 and 34 which rise from the plate 30 and the upper ends of which are threaded and received in threaded openings 35 in the top plate 29. The 30 upright stem 21 is carried by or formed integral with the top plate 29. Secured as by screws 36 to the underside of the bottom plate 30 is the presser foot proper 37 having an angular extension to engage the work W immediately below 35 the clamping jaws hereinafter described and press said work against the work plate 16, said extension being cut away as shown at 38 to permit the action of the sewing instrumentalities. Guided for rectilinear movement between the plates 29 and 30 in directions to carry their forward ends toward and away from one another, are three slides 39, 40 and 41 carrying the button clamping jaws. The slide 39 is guided in a way 45 42 formed in the underside of the top plate 29 50 55

for movement in a direction longitudinally of the machine. The slide 40 is provided with slots 43 and 44 which are guided on rollers 45 and 46 carried by the studs 33 and 31 respectively. Similarly the slide 41 is formed with slots 47 and 48 guided on rollers 49 and 50 carried by the studs 32 and 34. The slides 39, 40 and 41 are formed with racks 51, 52 and 53 which cooperate with and are connected by a common pinion 54 rotatably mounted on a stud 55 depending from the top plate 29, whereby the rectilinear movements of the several slides are in unison. The relative arrangement of the way 42, the studs 31, 32, 33 and 34, and the slots 43, 44, 47 and 48 in the slides 40 and 41 is such that the rectilinear movements of the several slides are in directions at 120° to each other. In other words, the paths of movement of said slides or jaw carriers are radial to a common center and disposed at substantially equal angles thereabout. The several slides are formed with depending end portions 56 by which the clamping jaws hereinafter described are carried. Consequently, movement of the slides causes said clamping jaws to move in unison toward and from one another and toward and from a button interposed between them in rectilinear directions radial of the button and to engage the latter at points substantially equally spaced about the periphery of the latter. This action causes the button to be accurately positioned or centered and to be securely held to a degree greater than is possible in any prior button holding device of which we are aware.

Each button clamping jaw comprises upper and lower button engaging members 57 and 58 adapted respectively to engage opposite sides of the edge of the button, thereby securely holding the same and positioning it vertically. The members 57 and 58 are vertically adjustable on the portions 56 of the slides independently of each other, adjustment of the member 58 determining the position of the button above the work and consequently the length of the connecting neck or shank, and adjustment of the member 57 with respect to the member 58 adapting the clamps to buttons of different thickness.

Referring to Fig. 6, the jaw members 57 and 58 carried by the slides 40 and 41 are provided with upright angular portions 59 and 60 respectively which are received in vertical ways 61 in the portions 56 of said slides and are secured in adjusted position therein by screws 62 in threaded engagement with the portions 59 and passing through slots 63 and 64 in the portions 56 and 60. The mounting of the jaw members on the slide 39 is similar to the foregoing with the exception that, as shown in Figs. 5 and 8, the upright portion 59a of the member 57 is formed with flanges embracing the depending portion 56 of the slide and the upright portion 60 of the member 58, and the screw 62a is threaded into the portion 56 and passes through a slot in the portion 59a.

The slides are normally urged in the direction to cause the jaws to approach one another and engage the button by means of a torsion spring 65 coiled about a stud 66 fast in a lug 67 rising from the top plate 29, said spring being secured at one end to said stud and at its opposite end engaging the rear face of a lug 68 projecting upwardly from the slide 39 through a slot 69 in the top plate 29. The spring 65 acts normally to urge the slide 39 forwardly, and, since the three slides are connected for movement in unison through their racks and common pinion 54,

to cause the three jaws to approach one another in unison and in a radial rectilinear direction as above described.

The closing movement of the jaws under the influence of the spring 65 is limited in accordance with the diameter of the button by an adjustable abutment screw 70 in threaded engagement with an upturned lug 71 at the rear end of the slide 39 and the forward free end of which engages the lug 67 to limit the forward movement of the slide 39.

Pivotedly mounted on the stud 66 is a bell crank lever 72 one arm of which engages the forward face of the lug 68 and the other arm of which is adapted, when the clamps are raised by the treadle 27, to engage an adjustable abutment screw 73 (Figs. 1 and 4) depending from the machine head 17, thereby causing said lever to be rocked about its pivot to force the slide 39 rearwardly and separate the clamping jaws. The arrangement is such as to provide lost motion between the lever 72 and abutment screw 73 the amount of which is variable by adjusting said screw, so that the maximum opening of the clamp for a given lifting movement thereof can be determined in accordance with the diameter of the button.

As shown most clearly in Fig. 1a, the arm 22 which connects the stem 21 with the slide 23, is formed adjacent its ends with circular openings 30 15 and 16 to receive cylindrical portions of said stem and slide, respectively, the ends of the arm beyond said openings being split, as shown at 77 and 78, and provided with clamping screws 79 and 80, so that by loosening said screws the angular positions of the stem 21 in the opening 15 and of the arm on the slide 23 can be varied, the parts being thereafter clamped in adjusted position by tightening said screws. Angular adjustment of the stem 21 with respect to the arm 22 provides a lateral adjustment of the clamping jaws as indicated by the arrow X, while angular adjustment of the arm with respect to the slide 23 provides a longitudinal adjustment of said jaws as indicated by the arrow Y. The construction therefore permits universal adjustment in a horizontal plane of the button clamp as a whole with respect to the needle and other stitch-forming instrumentalities, both in assembling and for the purpose of adapting the machine to buttons of different shapes and hole arrangements.

We claim:

1. A button clamp comprising at least three button engaging jaws relatively movable toward and from each other and supporting means therefor constructed and arranged to cause the relative movements of said jaws to take place along rectilinear paths radial to a common center and forming substantially equal angles with each other.

2. A button clamp comprising at least three button engaging jaws, a plurality of slides by which said jaws are carried respectively, and means for guiding said slides for movements in rectilinear paths radial to a common center and forming substantially equal angles with each other.

3. A button clamp comprising at least three button engaging jaws relatively positioned to engage a button at substantially equally spaced points about its periphery and means for relatively moving said jaws toward and from each other to clamp and release the button.

4. A button clamp comprising at least three button engaging jaws relatively positioned to en-

gage a button at substantially equally spaced points about its periphery and means for relatively moving said jaws toward and from each other in rectilinear paths radial to a common center to clamp and release the button.

5. A button clamp comprising at least three button engaging jaws spaced at substantially equal angles about a common center, slides by which said jaws are respectively carried, said slides being 10 guided for movement to cause said jaws to move toward and from each other, and means connecting said slides for movement in unison.

15. A button clamp comprising a plurality of button engaging jaws, slides by which said jaws are respectively carried, said slides being guided for movement to cause said jaws to move toward and from each other, said slides having racks, and a common pinion engaging and connecting the several racks.

20. A button clamp comprising a plurality of jaws adapted to grip between them the edge of a button and thereby fix its position, carriers for said jaws, and means for adjustably securing said jaws to said carriers, whereby the position of said 25 button with respect to said carriers may be varied.

25. A button clamp for holding and positioning a button with respect to work to which it is to be attached, said clamp comprising a plurality of button engaging jaws and carriers therefor, each of said carriers having a portion disposed substantially perpendicular to the work, and means for attaching said jaws to the perpendicular portions of their respective carriers in variable positions longitudinally of said portions.

30. A button clamp comprising a plurality of button engaging jaws and carriers therefor, each of said jaws comprising two members adapted respectively to engage opposite sides of the edge of the button, said members being independently 35 adjustable on the carrier in the direction of the thickness of the button.

35. A button clamp for holding and positioning a button with respect to work to which it is to be attached, said clamp comprising a plurality of button engaging jaws and carriers therefor, each of said carriers having a portion disposed substantially perpendicular to the work, and each of said jaws comprising two members adapted respectively to engage opposite sides of the edge of 40 the button, and means for attaching said members to said perpendicular carrier portion in independently variable positions longitudinally thereof.

45. 11. In a button attaching machine having work-supporting means, a button clamp comprising a plurality of button engaging jaws and car-

riers therefor, and means for supporting said clamp, certain of said parts being adjustable to vary the distance from said work-supporting means of a button held by said jaws.

5. 12. In a button sewing machine, the combination with stitch-forming instrumentalities, of a button clamp having button receiving jaws universally adjustable with respect to said instrumentalities.

10. 13. In a button sewing machine having stitch-forming instrumentalities including a needle having work-penetrating movements, a button clamp, and means for supporting said clamp adjustable to vary the position of said clamp universally in a direction transverse to the direction of the work-penetrating movements of said needle.

15. 14. In a button sewing machine having stitch-forming mechanism and a work support, a button clamp and means for supporting the same comprising a plurality of adjustably connected members, one of the connections permitting adjustment in one direction in a plane substantially parallel with work on said support, and another of the connections permitting adjustment in said plane in a direction transverse to said first named 20 direction, whereby said clamp is universally adjustable in said plane.

20. 15. In a button attaching machine, a button clamp assembly having a stem, an arm in which said stem is angularly adjustable, and a slide on 25 which said arm is angularly adjustable.

25. 16. A button clamp comprising at least three button engaging jaws relatively movable toward and away from each other and supporting means therefor constructed and arranged to cause said 30 jaws to engage a button at substantially equally spaced points about its periphery when relatively moved toward each other.

30. 17. A button clamp comprising at least three button engaging jaws relatively positioned to 35 engage a button at substantially equally spaced points about its periphery, at least two of said jaws being movable in paths substantially radial to the center of the button at their respective points of engagement therewith.

40. 18. A button clamp comprising at least three button engaging jaws relatively positioned to engage a button at substantially equally spaced points about its periphery, said jaws being movable in paths substantially radial to the center 45 of the button at their respective points of engagement therewith, and means connecting said jaws for movement in unison toward and away from said center.
